(57) **CLAIM**

The ornamental design for a curtain rod mounting device as shown and described.

DESCRIPTION

FIG. 1 is an isometric view of the curtain rod mounting device;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The fastener components shown in broken line in FIGS. 1-7 form no part of the claimed design.

1 Claim, 3 Drawing Sheets
